UNITED STATES PATENT OFFICE.

JAMES A. MACKENZIE, OF MINNEAPOLIS, MINNESOTA, ASSIGNOR TO JOHN J. COMSTOCK, ALBERT W. STORMS, AND JOHN H. WILLARD, OF CHICAGO, ILLINOIS.

HINGE-MORTISING MACHINE.

SPECIFICATION forming part of Letters Patent No. 437,657, dated September 30, 1890.

Application filed February 1, 1890. Serial No. 338,926. (No model.)

To all whom it may concern:

Be it known that I, JAMES A. MACKENZIE, of Minneapolis, Minnesota, have invented certain new and useful Improvements in Hinge-Mortising Machines, of which the following is a specification.

My present invention is an improvement upon the mortising-machine described in Patent No. 355,272, issued to me December 28, 1886; and the principal improvement consists in certain features of construction whereby the device is adapted to cut gains or mortises of different lengths. In my present construction I provide a knife-stock having one or both of its end walls movable laterally, and then by introducing front and sliding knives of different widths it is perfectly adapted to cut gains or mortises of different lengths.

A further improvement consists in adapting the pivoted lever, which is used to actuate the sliding knife, to be moved aside to permit the sliding knife to be taken out and a knife of different width substituted. This I do by pivoting the handle upon a rod of such length that said handle may be moved laterally to take its lower end out of engagement with the rack on top of the sliding knife, and thereby free the latter so that it can be removed. I preferably hold the handle normally in engagement with the sliding knife by means of a spring, which will yield to permit the knife to be moved out of engagement when desired. In my said former patent I described as a means for cutting the gain deeper at its outer edge than at its inner a sliding knife held in an inclined position. In my present construction I secure the same result by a different arrangement, viz: I provide the depth-gage with bearing-feet, which are inclined upwardly on their bearing-surfaces from the outer toward the inner ends, and thereby the knives are tilted with their cutting-edges at an angle to the horizontal, so that the chip removed is thicker on one edge than the other, and the mortise produced by the machine is deeper on its outer than its inner edge. I also provide a depth-gage of improved construction.

In the accompanying drawings, Figure 1 is

a side elevation of the device; Fig. 2 a rear elevation; Fig. 3 a bottom plan view. Fig. 4 is a front elevation. Fig. 5 is a side elevation, partly in section. Fig. 6 is a detail view of one of the adjustable walls of the knife-stock, and Fig. 7 is a cross-section through a block in which a gain or mortise has been cut.

In the drawings, 8 represents the main frame of the device, and it has a rigid handle 9, by which it may be grasped, and which serves as a head-stock or bearing to take the blows of the mallet. At the rear the frame is bifurcated, and the bifurcations (marked 10) have ways 11 formed therein for the sliding knife, as hereinafter described. At the front of the frame there is a vertically-projecting member 12, which forms a stock for the front knife 13, which makes a longitudinal cut in forming the gains or mortises. 14 is a stock for holding the transverse cutting-knives, and it consists of a head having a slot to receive the knife and a right angular extension 15. This block or stock 14 will move with its flat side against a flat portion of the frame beneath the handle and its fellow will be correspondingly formed. The angular portions 15 will lap by each other and be secured by a wedge-shaped screw 16, which passes between them and impinging on their beveled edges forces them outwardly—one against the rear wall of the frame and the other against the front knife—thereby not only securing them in place, but also securing the front knife in position. By loosening this screw the side knives may be adjusted to and from each other and a front knife of suitable length introduced to form any length of gain or mortise desired.

17 is a sliding knife moving freely in the ways 11, and which is actuated by a lever 18, turning freely on a fixed rod 19, secured on ears 20, projecting from the frame. The lower end of the lever engages the rack-teeth 17 on the top of the knife, and by operating the lever the knife may be moved in to cut out the chip. To permit of the removal and insertion of the sliding knife, the rod 19 is of such length that the lever may be moved laterally thereon to take its lower end out of en-

gagement with the rack-teeth, and to do this I prefer to confine the knife in its operative position by means of the coiled spring 22, having one end confined against the lug and 5 the other bearing against the lever, as shown in Fig. 4.

23 is a depth-gage, held to the frame by means of the set-screws 24, which pass through elongated openings 25 in the gage and are 10 tapped into the frame. The frame is recessed to receive the depth-gage, and the recess is provided with inclined sides, the cross-bar of the depth-gage being correspondingly inclined and fitted into said recess. By loosening the 15 screws and moving said bar the one way or the other along the inclined recess it is evident that the depth of the cut may be regulated.

The bearing-feet have their lower ends inclined upwardly from front to rear, and it is 20 evident that when they come to rest upon a plane surface the knives will be in angular position with reference to said surface. From this it results that the outer side of the gain 25 will be cut deeper than the inner side. If it be desired to cut a gain of uniform depth, the bearing-feet will be parallel to the sliding knife. I also provide a width-gage 26 and the chip-expeller 27, which are similar to those 30 described in my previous patent.

I claim—

1. In a device for forming hinge-mortises, the combination, with the frame having an operating-handle, of a stationary knife-stock 35 for the front knife, laterally-adjustable stocks for the side knives, and a sliding knife mounted in ways of the frame and adapted to be projected between the side knives, substantially as described.
2. In a device for forming hinge-mortises, 40 the combination, with the frame having a sta-

tionary stock for holding the front knife, of one or more movable stocks for holding the side knives, a removable sliding knife, and an operating-lever for moving said knife, substantially as described. 45

3. In a hinge-mortiser, the combination, with the cutting-knives, of a depth-gage having bearing-feet inclined from front to rear and an inclined cross-bar fitted to an inclined way 50 of the frame and secured thereto by screws passing through elongated apertures in the cross-bar, whereby mortises of different depths may be cut, substantially as described.

4. In a hinge-mortiser, the combination, with 55 the operating-knives, of a depth-gage having its bearing-feet inclined from front to rear, whereby the device is adapted to cut a mortise thicker at its outer than at its inner side, substantially as described.

5. In a hinge-mortiser, the combination, with the front and side knives and a sliding knife movable in ways of the frame, of an operating-lever for said sliding knife pivoted between its ends upon a fulcrum-rod and adapted 65 to be moved laterally along said rod to take its lower end out of engagement with the sliding knife, substantially as described.

6. In a hinge-mortiser, the combination, with the front and side knives and a sliding knife 70 movable in ways in the frame, of an operating-lever for said sliding knife pivoted between its ends upon a fulcrum-rod and adapted to be moved laterally along said rod to take its lower end out of engagement with the 75 sliding knife, and a spring adapted to hold said lever normally in engagement with the knife, substantially as described.

JAMES A. MACKENZIE.
